2,417,314

PORTABLE RANGE UNIT WITH SEPARATELY CONTROLLED FLUES

Robert Mallan, New York, N. Y.; Jane Mallan
executrix of said Robert Mallan, deceased

Application March 6, 1943, Serial No. 478,275

10 Claims. (Cl. 126—268)

1

This invention relates to apparatus commonly referred to as ranges, and particularly to a portable unit of this kind mounted on wheels to facilitate transportation or movement of the range from place to place, thus adapting it for practical military purposes in providing all necessary equipment for the preparation of food supply to the army. The object of the invention is to provide units of the class described having containers, compartments, pots, tanks or the like whereby all kinds and descriptions of foods can be prepared, including the supply of hot water. A further object being to provide units of the class described in which the burner and source of fuel, compressed air and steam all constitute an integral part of the portable unit as more fully hereinafter described.

The novel features of the invention will be best understood from the following descriptions when taken together with the accompanying drawing in which certain embodiments of the invention are disclosed, and in which the separate parts are designated by suitable reference characters in each of the views, and in which:

Fig. 1 is a diagrammatic plan view of a unit made according to my invention.

Fig. 2 is a cross section substantially on the line 2—2 of Fig. 1.

Fig. 3 is a sectional view substantially on the line 3—3 of Fig. 2,

Fig. 4 is a sectional view substantially on the line 4—4 of Fig. 2, and

Fig. 4a is a partial section on the line 4a—4a of Fig. 4.

While my improved range is adaptable for many uses, either as a portable or stationary apparatus, for the purposes of this description, and to illustrate one adaptation of the invention, the range will be described from a military standpoint and identified as a field range unit.

With field ranges which have been put into military use, it has recently been practiced to employ rather large cumbersome ranges fired by gasoline burners. These ranges in addition to being very inefficient have also been extremely objectionable by reason of the danger of explosion, and by a lack of mobility in rough terrain. Further, expert care and constant cleaning has been necessary in the attempt to maintain a reasonable degree of efficiency in such type of apparatus.

2

It is the purpose of my invention to construct a very simple and highly efficient range made in the form of a portable unit, which can be quickly and easily shifted from place to place. Further, it is my purpose to employ a unit of this kind having a fuel oil burner using fuel oil, whereby in addition to providing a high degree of efficiency and practicability resulting from the simple construction and portable characteristics of the range, also effects a material saving in fuel consumption. It is also well to mention that a unit of the kind under consideration will operate efficiently with a minimum amount of care, and will not require the cleaning and alterations as usually found necessary with other apparatus of this kind.

With my range unit, many of the containers, pans and the like are removable to facilitate periodic cleaning of the interior of the range. Further, the range is so designed, that the pots and pans partially form the heat circulating chambers of the range, baffle or partition walls being employed to control circulation of the heat units through the range, and finally through the smoke stack or chimney. It is also well to point out that the fuel oil burner employed is generally of the type and kind disclosed in my Patent 2,304,468, dated December 8, 1942, and for this reason, no specific disclosure of the burner will herein be made. This type of burner operates without the use of any electric motor or similar secondary power source.

The illustrations in the accompanying drawings are somewhat diagrammatic, particularly from the standpoint of showing the detailed construction of the various insulated and other walls of the range in order to simplify the present illustration.

The range unit comprises an oblong rectangular range body 10, and for purposes of this description, the wall 11 will be regarded as the front wall, the wall 12 the back wall, and 13 and 14 will represent the side walls. Suitably supported on the side walls 13—14 are axles 15, on which are mounted a yoke shaped hauling frame 16, note Fig. 1, and outwardly of the frame 16, are large wheels 17 by means of which the range unit may be moved over a surface in the transportation thereof.

Hingedly supported on lower corners of the body 10 are feet 18 normally held in raised positions

in the transportation of the unit and adapted to be lowered when the unit is at rest to maintain the body 10 against swinging movement.

Central of the lower portion of the body 10 is a fire box 19, the greatest depth of which extends between the front and the back walls. This fire box flares upwardly to the side walls 13-14, as will clearly appear from a consideration of Fig. 2 of the drawing. Means is provided as at 20 to support a grate in the lower portion of the fire box in the event that it is desirable to use wood or coal as fuel. In which event, the lower part 21 below the fire box becomes an ash pit. For military purposes, a grate 22 may be installed to have the same in readiness for instantaneous use by simply removing the oil burner 23. When the burner is in use, it is also preferred that an asbestos or other facing 22-a be arranged over the grate, as indicated in Fig. 2 only. This facing is omitted from Figs. 3 and 4.

The burner 23 is suitably mounted on the front wall 11 of the range body, and supported on the wall above the burner is a fuel oil supply tank 24, which provides a gravity feed to the burner. At 25 is shown the boiler or steam generator for supplying steam to the nozzle 23-a of the burner. The burner is of the general type and kind identified in the patent above mentioned.

In the present adaptation of the invention the nozzle 23-a opens into a mixing chamber 23-b, in which is arranged a primer or booster 23-c, used to start the burner and in generating initial steam supply. The flame of this primer extends into the mixing chamber and out through the discharge 25-a, which is built within the steam generator 25. With this construction the heat of the flame will maintain the generator 25 in constant operation. The above structure is only diagrammatically illustrated for purposes of clarity in understanding of the complete apparatus.

Adjacent the side 14 of the body 10 is a compartment 26, in which a water pressure tank 27 is mounted, and this compartment may also be used as a storage means for tools and equipment. At 28 is shown a handle of a hand pump for supplying the required pressure to the tank 27 for pressure feed of the water to the boiler. At the other side of the body 10, adjacent the wall 13 is a tool or other storage compartment 29.

The main control for the burner is indicated by the knob 30, and arranged around the burner inwardly of the knob is an air housing or jacket 31, which prevents high winds from materially effecting burner operations. In many instances, the range unit will be operated out of doors, and when high winds prevail, it is desirable to shield the burner from the wind.

In the construction shown, a hot water tank 32 is exposed to the fire box, and water may be supplied to this tank through an inlet, as at 33, and discharged therefrom through a faucet or valve 34. This water may be used in the preparation of foods, in the making of tea and other hot drinks, and in delivering hot water for cleaning and other purposes.

In addition to the water tank, the upper portion of the body 10 is divided into different types of compartments for the preparation of different foods. For example, a large soup pot 35 is supported in the front portion of the body adjacent the wall 13, whereas a coffee pot or kettle 36 is supported just rearwardly of the pot 35. At the top of the body 10, adjacent the wall 14, and extending between the front and back walls 11 and 12, is a large frying pan 37. The pot 35, as well

as the pan 37 all have removable covers to render the interior of the various receptacles accessible through the top of the unit, and suitable means may be provided to retain these covers against accidental displacement, particularly in transportation of the unit with food in the various receptacles. As is well known in other arts, means may be provided to seal the covers so that any fluid contents will not be discharged. As these details form no part of the present invention, they are not specifically shown.

While the water tank 32, and the coffee kettle 36 are more or less of a fixture in the range, the pot 35, as well as the pan 37 are made removable, and are so mounted as to form around the same, circulating chambers, the circulating chambers of the pot 35 are generally indicated by the reference character 38. The baffles 39 and partition 39a are employed, note Figs. 2, 4 and 4a, to provide a back and forth retarded circulation substantially as indicated by the arrows 40 in Figs. 2 and 4, as well as in Fig. 3.

At 41 is shown a baking oven, this is also a more or less built in structure, and so arranged with respect to the water kettle and the frying pan as to provide a circulating chamber 42 below the oven, a circulating chamber 43 above the oven, other chambers 44, at each side of the oven, and a chamber 45 at the back of the oven. A hinged door 46 is arranged upon the front wall 11 to control admission to the oven chamber.

Sub-dividing the pot side from the frying pan side is a back and forth partition 47, and this partition is offset at the back of the water tank 32, as seen at 48, and where it opens into a flue discharge 49 at the back of the fire box 19.

Pivoted at one side of the wall 47-48 is a damper 50, which controls the discharge of products of combustion from the fire box through the discharge 49 up into the oven side of the range. Another damper 50-a is arranged at the other side of the wall 47-48, and operates between the tanks 35, 36, note Fig. 4, in controlling circulation of products of combustion to the side of the range in which the pots 35, 36 are disposed. The dampers have suitably operated knobs outwardly of the wall 12, as indicated in Figs. 3 and 4 of the drawing. At 51 is shown an opening controlled by the damper 50 so that products of combustion from the fire box can rise upwardly for circulation around the pots 35, 36.

By throwing the damper 50-a into closed position, all of the heat will be circulated around the oven and beneath the frying pan, as will be apparent. On the other hand, by closing the damper 50, all of the heat may be directed through the discharge 51 with the damper 50-a in open position. Of course, when both dampers are in open position the heat will be circulated around all of the compartments, containers and so forth.

The exposure of both of the bottoms of the pots 35, 36 to the fire box will naturally heat any food products or beverages that may be contained therein. This would operate to keep them warm while baking or frying, or these pots or compartments thereof may simply be kept idle.

Built into the upper central portion of the range in line with the partitions 47 are two flue discharges 52. These discharges terminate short of the front wall 11, as indicated at 53, in Fig. 3 of the drawing, and products of combustion from one side of the range pass out through one passage 52, and from the other side of the range through the other passage 52, and these two 75 passages lead into a single vertical stack dis-

charge 54, which is comparatively short in height. This is made possible by virtue of the length of the flue formed by the two passages 52 which actually constitute part of the stack. By being built into the upper portion of the range, the horizontal flue discharges 52 also will radiate heat to produce efficient range operation.

The circulation of the products of combustion indicated by the arrows 40 produces in the resulting range a very high efficiency in operation for cooking, baking and frying, and this has been verified by carefully checked tests made on the range unit.

Instead of operating the burner unit with the heavier types of fuel, such as Number 2, or Number 3 furnace oil, lighter grades of fuel may be used, including gasoline. With some of these lighter fuels, and particularly gasoline, I find it desirable to put the fuel in the tank 24, under pressure, and this is done by simply adding an air hand pump 55, the discharge 56 of which opens into the upper part of the tank, and suitable well known valves will be employed to hold the pressure in the tank, appropriate pressure gages and the like may be employed.

I have also found that mixtures of light and heavy fuels can be employed, as well as a mixture of gasoline and lubricating oils.

It will, of course, be apparent that in the use of the different types and kinds of fuel, the burner will be adjusted to control the various feeds and the relative positions of the nozzles.

It will be apparent that location and arrangement of the various tanks, pots, pans and so forth may be varied to suit different users, and when it is desired to concentrate the unit on the preparation of certain types and kinds only of food, that the more general combination as herein indicated can be dispensed with, but in all instances, the general structure of the range will be the same.

It will be understood that the outer walls of the range body will be suitably insulated, and the fire box will be lined with suitable material, as is common with structures of this type and kind.

Having fully described my invention, what I claim as new and desire to secure by Letters Patent is:

1. A range comprising an insulated body, a fire box at the lower portion of said body, the body above the fire box having a partition wall intermediate the side walls and substantially centrally of the body, receptacles in said body in spaced relation to the outer walls thereof and said partition wall to form at each side of the partition wall independent circulating passages, part of said circulating passages being disposed at opposite sides of said partition wall, the rear portion of the fire box having an outlet communicating with the circulating passages at each side of said partition, manually operated means adjacent the partition controlling circulation of products of combustion in each of said circulating passages, baffles in said circulating passages for retarding circulation of products of combustion upwardly through said passages and around said receptacle, the upper portion of said body having a horizontal flue comprising flue passages adjacent and at opposite sides of said partition, means discharging products of combustion from each of said circulating passages into one end of the horizontal flue passages, and a vertical stack communicating with the other end of said horizontal flue passages.

2. A range comprising an insulated body, a fire box at the lower portion of said body, the body above the fire box having a partition wall intermediate the side walls and substantially centrally of the body, receptacles in said body in spaced relation to the outer walls thereof and said partition wall to form at each side of the partition wall independent circulating passages, part of said circulating passages being disposed at opposite sides of said partition wall, the rear portion of the fire box having an outlet communicating with the circulating passages at each side of said partition, manually operated means adjacent the partition controlling circulation of products of combustion in each of said circulating passages, baffles in said circulating passages for retarding circulation of products of combustion upwardly through said passages and around said receptacles, the upper portion of said body having a horizontal flue comprising flue passages adjacent and at opposite sides of said partition, means discharging products of combustion from each of said circulating passages into one end of the horizontal flue passages, a vertical stack communicating with the other end of said horizontal flue passages, and said circulating passages extending to substantially completely envelope wall portions of said receptacles.

3. A range comprising an insulated body, a fire box at the lower portion of said body, the body above the fire box having a partition wall intermediate the side walls and substantially centrally of the body, receptacles in said body in spaced relation to the outer walls thereof and said partition wall to form at each side of the partition wall independent circulating passages, part of said circulating passages being disposed at opposite sides of said partition wall, the rear portion of the fire box having an outlet communicating with the circulating passages at each side of said partition, manually operated means adjacent the partition controlling circulation of products of combustion in each of said circulating passages, baffles in said circulating passages for retarding circulation of products of combustion upwardly through said passages and around said receptacles, the upper portion of said body having a horizontal flue comprising flue passages adjacent and at opposite sides of said partition, means discharging products of combustion from each of said circulating passages into one end of the horizontal flue passages, a vertical stack communicating with the other end of said horizontal flue passages, said circulating passages extending to substantially completely envelope wall portions of said receptacles, one of said receptacles at one side of the body comprising a baking oven, and the circulating passages of said side of the body completely enveloping all but the front wall of said oven.

4. A range comprising an insulated body, a fire box at the lower portion of said body, the body above the fire box having a partition wall intermediate the side walls and substantially centrally of the body, receptacles in said body in spaced relation to the outer walls thereof and said partition wall to form at each side of the partition wall independent circulating passages, part of said circulating passages being disposed at opposite sides of said partition wall, the rear portion of the fire box having an outlet communicating with the circulating passages at each side of said partition, manually operated means adjacent the partition controlling circulation of products of

combustion in each of said circulating passages, baffles in said circulating passages for retarding circulation of products of combustion upwardly through said passages and around said receptacles, the upper portion of said body having a horizontal flue comprising flue passages adjacent and at opposite sides of said partition, means discharging products of combustion from each of said circulating passages into one end of the horizontal flue passages, a vertical stack communicating with the other end of said horizontal flue passages, said circulating passages extending to substantially completely envelope wall portions of said receptacles, and one of said receptacles comprising a frying pan.

5. A range comprising an insulated body, a fire box at the lower portion of said body, the body above the fire box having a partition wall intermediate the side walls and substantially centrally of the body, receptacles in said body in spaced relation to the outer walls thereof and said partition wall to form at each side of the partition wall independent circulating passages, part of said circulating passages being disposed at opposite sides of said partition wall, the rear portion of the fire box having an outlet communicating with the circulating passages at each side of said partition, manually operated means adjacent the partition controlling circulation of products of combustion in each of said circulating passages, baffles in said circulating passages for retarding circulation of products of combustion upwardly through said passages and around said receptacles, the upper portion of said body having a horizontal flue comprising flue passages adjacent and at opposite sides of said partition, means discharging products of combustion from each of said circulating passages into one end of the horizontal flue passages, a vertical stack communicating with the other end of said horizontal flue passages, said circulating passages extending to substantially completely envelope wall portions of said receptacles, and one of said receptacles comprising a kettle.

6. In a range having a fire box at the lower portion thereof with a discharge from the fire box at the rear of the range, the range above the fire box being divided by a substantially central vertical partition wall and by receptacles in the range, in spaced relation to the walls of the range and said partition wall, into independent circulating passages with which the discharge from the fire box communicates, a horizontal flue passage at each side of the partition at the top of the range, one end of each flue passage registering with the circulating passage on the corresponding side of said partition for providing exhaust of products of combustion therefrom, and a vertical discharge at the other end of the horizontal flue passage.

7. In a range having a fire box at the lower portion thereof with a discharge from the fire box at the rear of the range, the range above the fire box being divided by a substantially central vertical partition wall and by receptacles in the range, in spaced relation to the walls of the range and said partition wall, into independent circulating passages with which the discharge from the fire box communicates, a horizontal flue passage at each side of the partition at the top of the range, one end of each flue passage registering with the circulating passage on the corresponding side of said partition for providing exhaust of products of combustion therefrom, a vertical discharge at the other end of the horizontal flue passage at each side of the partition at the top of the range, one end of each flue passage registering with the circulating passage on the corresponding side of said partition for providing exhaust of products of combustion therefrom, and a vertical discharge at the other end of the horizontal flue passage.

8. In a range having a fire box at the lower portion thereof with a discharge from the fire box at the rear of the range, the range above the fire box being divided by a substantially central vertical partition wall and by receptacles in the range, in spaced relation to the walls of the range and said partition wall, into independent circulating passages with which the discharge from the fire box communicates, a horizontal flue passage at each side of the partition at the top of the range, one end of each flue passage registering with the circulating passage on the corresponding side of said partition for providing exhaust of products of combustion therefrom, a vertical discharge at the other end of the horizontal flue passage, and manually adjustable means for controlling circulation of products of combustion from the fire box to the circulating passages at each side of said partition.

10. In a range having a fire box at the lower portion thereof with a discharge from the fire box at the rear of the range, the range above the fire box being divided by a substantially central vertical partition wall and by receptacles in the range, in spaced relation to the walls of the range and said partition wall, into independent circulating passages with which the discharge from the fire box communicates, a horizontal flue passage at each side of the partition at the top of the range, one end of each flue passage registering with the circulating passage on the corresponding side of said partition for providing exhaust of products of combustion therefrom, a vertical discharge at the other end of the horizontal flue passage, and manually adjustable means for controlling circulation of products of combustion from the fire box to the circulating passages at each side of said partition, and means retarding circulation of products of combustion through said passages and around said receptacles.

9. A portable range unit comprising a wheeled body, a fire box at the lower portion of said body with a discharge from the fire box at the rear of the range, means for supporting a complete burner system on said body for firing said fire box, said last named means including means on the body for supporting a supply of compressed air and water, the range above the fire box being divided by a substantially central vertical partition wall and by receptacles in the range, in spaced relation to the walls of the range and said partition wall, into independent circulating passages with which the discharge from the fire box communicates, a horizontal flue passage at each side of the partition at the top of the range, one end of each flue passage registering with the circulating passage on the corresponding side of said partition for providing exhaust of products of combustion therefrom, a vertical discharge at the other end of the horizontal flue passage, and a damper controlling the discharge of products of combustion from the fire box to the circulating passages of said unit.

10. In a self-fired portable field range unit employing a burner and fuel, water and compressed air supplies thereto; a range body, a fire box in the lower portion of said body fired by said burner, the range body above the fire box having a central vertical partition and receptacles at each side of the partition spaced therefrom and from the walls of said body to form independent circulating passages at each side of the body, means including a manually actuated member for controlling passage of products of combustion from the rear portion of the fire box into said circulating passages, the circulating passage at each side of said partition having a horizontal discharge flue adjacent the partition at the top of the range body with an exhaust from the circulating passage to the flue at one end thereof, the other end of each flue communicating with a vertical stack, and means retarding circulation of products of combustion through each of said circulating passages.

70 ROBERT MALLAN.
